United States Patent Office.

DAVID HATHAWAY, OF TROY, NEW YORK, ASSIGNOR TO FULLER, WARRIOR AND COMPANY, OF SAME PLACE.

Design No. 2,752, dated August 20, 1867.

DESIGN FOR THE PLATES OF A STOVE.

The Schedule referred to in these Letters Patent and making part of the same.

TO ALL WHOM IT MAY CONCERN:

Be it known that I, DAVID HATHAWAY, of the city of Troy, in the county of Rensselaer, and State of New York, have invented or produced a new and original ornamental Design for Plates of a Stove, of which following is a full and exact description, reference being had by letters to the accompanying photographs, which—

Figure 1 represents a front plate,

Figure 2 an end plate,

Figure 3 a top plate, and

Figure 4 the cap or urn plates of a stove having my said design.

The ornamental design of the front plate A consists of three arched mouldings *b* and *b'* *b''* over the ornaments *c* and *c'* *c''*, the two ornamental pillars or pilasters *d* *d'*, and the oval surfaces *e* *f* *g* *h* on the raised ornamental panel *i*, all shaped and arranged on the plate A so as to present the appearance represented in fig. 1. The ornamental design of the end plate B consists of the ornaments *j* *j'*, a representation of a projecting window, *k*, with zigzag ornaments *l* and mouldings *m* on its frame, and the ornamental base *n*, and lower ornamental panels *o* *o'* *o''*, all shaped and arranged on the plate B as shown in fig. 2. The ornamental design of the top plate C consists of the raised ornamental internal ledge portion *p*, and lower border portion, having thereon the ornaments *q*, the whole shaped and arranged so as to appear as shown in fig. 3. And the ornamental design of the cap or urn plates D consists of the oval open-work part *r* between an outer moulding, *s*, and an inner moulding, *t*, and the open-work oval rim piece *u*, supported by the scroll leaves *v*, all shaped and arranged so as to appear as represented in fig. 4.

What I do claim as my invention and production, and desire to secure by Letters Patent, is—

The above-described ornamental design of the plates A, B, C, and D of a stove.

In testimony whereof I have hereunto set my hand this thirteenth day of July, 1867.

Witnesses:

LESLIE SMYTH,

AUSTIN F. PARK.

DAVID HATHAWAY.
